FOOTSTOOL

Ramon V. Dixon, Detroit, Mich.

Application October 27, 1954, Serial No. 32,837

Term of patent 14 years

(Cl. D15—8)

To all whom it may concern:

Be it known that I, Ramon V. Dixon, a citizen of the United States, and a resident of Detroit, county of Wayne, and State of Michigan, have invented a new, original, and ornamental Design for a Footstool, of which the following is a specification, reference being had to the accompanying drawing, forming a part hereof, and wherein the figure of the drawing is a perspective view of a footstool showing my new design.

I claim:

The ornamental design for a footstool, as shown.
